UNITED STATES PATENT OFFICE

2,021,169

STENCIL DUPLICATING MACHINE

Maurice B. Brand, Chicago, Ill., assignor of one-half to Louis H. Freise, Chicago, Ill.

Application December 7, 1934, Serial No. 756,421
In Canada May 7, 1934

2 Claims. (Cl. 101—116)

This invention relates to improvements in stencil duplicating machines and it consists of the matters hereinafter described and more particularly pointed out in the appended claims.

5 One of the objects of the invention is to provide an improved mounting for the impression roll of the machine, whereby the same is yieldingly held in a guided path so that it will adjust itself toward and away from the associated printing cylinder to accommodate the feeding of paper of different thicknesses as desired.

Still another object of the invention is to provide a mounting of this kind which includes impression roller bearing blocks, formed for guided engagement in openings in the side frames, in a manner preventing any undesired movement of the blocks that would tend to cause a binding thereof in the side frames, and which would result in the production of imperfect impressions.

20 A further object of the invention is to provide in a machine of this kind, a novel means for connecting the stencil and inking pad to the associated perforated supporting sheet or cylinder segment, to form a unit that may be quickly removed and replaced, thus making it practical to remove the unit and substitute a different one therefor, in multi-color ink work.

The above mentioned objects of the invention, as well as others, together with the many advantages thereof, will more fully appear as I proceed with my specification.

In the drawing:

Fig. 1 is a view in side elevation of a stencil duplicating machine embodying the preferred form of the invention;

Fig. 2 is a fragmentary view in elevation, illustrating the manner of attaching one end of an ink pad and a stencil to the associated end of a perforated supporting member or cylinder segment;

Fig. 3 is a fragmentary view in elevation, illustrating the manner of attaching the other end of the ink pad and the stencil to the associated end of the perforated supporting member;

Fig. 4 is a detail sectional view through a part of the machine on an enlarged scale as taken on the line 4—4 of Fig. 1;

Fig. 5 is a detail sectional view on an enlarged scale as taken on the line 5—5 of Fig. 3; and

Fig. 6 is a detail sectional view also on an enlarged scale as taken on the line 6—6 of Fig. 2.

Referring now in detail to that embodiment of the invention, illustrated in the accompanying drawing:

55 1 indicates one of the side plates of the ma-

chine, each preferably made as a sheet metal stamping. Each side plate is provided at the top, on the outside thereof, with a bearing bushing 3. Journalled in said bushings is a horizontal shaft 9 for the cylinder 10, as a whole. To one end of said shaft, outside of one of the side plates is fixed a crank 11 by which the cylinder is rotated. Each bearing 3 is provided with an ear 12, the purpose of which will soon appear.

In each side plate is formed an opening 13 with 10 an enlarged bottom end 14, thus providing a shoulder 15 at the junction of said opening and its enlarged bottom end. The side edges 16 of the opening are parallel with a plane radial with respect to the shaft 9 and said plane is disposed 15 at an inclination to the perpendicular.

17 indicates a bearing block, there being one of such blocks associated with the opening 13 in each side plate. This block is provided in opposite sides with a groove 18 for sliding guided 20 engagement with those parts of each side plate defining the opening 13 therein. This block is so proportioned as to be capable of insertion into the enlarged bottom end 14 of an associated opening 13 and then moved upwardly therein so 25 as to engage the grooves 18 of the block with those portions of the side plate that define the side edges 16 of said opening 13. Journalled in said blocks are the ends of a horizontal shaft 17a. An impression roll 19 is fixed to said 30 shaft between said bearing blocks to cooperate with the cylinder 10. Each block is provided at its top end, outside the associated side plate, with an ear 20. A helical spring 21 has its ends engaged in associated ears 12 and 20 respectively. These springs normally act to hold the roll 19 in peripheral engagement with the cylinder and will yield to accommodate paper of different thicknesses as the same is fed to the machine.

On the bottom end of each block there is pivoted as at 22, a bell crank lever 23 (see Fig. 4). This lever includes a locking arm 24 and a manipulating arm 25. When it is desired to hold the impression roll 19 in spaced relation with respect to the cylinder 10, the blocks 17 are 45 moved downward in their openings 13 until the lever is arranged slightly below the shoulders 15. The arm 25 of each lever is then swung outwardly away from the associated side plate and this will bring the short arm into position to 50 engage one of the shoulders 15 before mentioned. This will hold the roll 19 spaced from the cylinder for cleaning and the like. To bring the impression roll back into operative relation with respect to the cylinder, the levers 23 are 55

manipulated to move the arms 24 out of engagement with the shoulders 15. The springs 21 then act to restore the roll 19 to its operative position with respect to the cylinder.

5 The cylinder 10 includes a pair of wheel-like end heads 26—26 each suitably fixed to the shaft 9 just within an associated side plate. Each end head also is provided with an inwardly extending segmental flange 27, for the detachable support of a duplicating unit in a manner presently to appear. Each unit includes a perforated, thin flexible metallic sheet 28 of a length approximating the peripheral length of the segmental flange 27. This sheet, which provides the supporting segment for the pad and the stencil of the machine, has imperforate margins 29 for engagement upon the flanges 27—27. The peripheral length of said flanges is such as to provide an opening in the cylinder for access 10 to the interior thereof when so desired. In each imperforate margin 29 of the sheet 28, are provided longitudinal slots 30 through which extend fastening devices 31 carried by the flanges 27. When the devices are disposed longitudinally of the slots 30, they can pass through the same to permit the removal and replacement of the sheet 28. After the sheet 28 has been thus applied the devices 31 are turned to stand transversely of the associated slots to lock the sheet 15 to the end heads.

That end of the sheet, which advances toward the impression roller 19 in the rotation of the cylinder 10, is formed to provide an inwardly depressed trough or groove 32 and an inwardly extending flange 33 that carries buttons 34 thereon. A part of the metal of the sheet 28 that is formed to provide the ends of the groove 32, is slit and upset outwardly to provide keeper ears 35—35, one arranged in the plane of each imperforate margin 29 of the sheet 28. The purpose of said ears will appear later.

The other end of said sheet 28 is formed to provide a deeper and wider groove 36 as best shown in Fig. 5.

45 37 indicates the ink pad supported upon the sheet or segment 28. This pad is only wide enough to cover the perforated portion of the sheet or segment and is provided at one end with a loop-like pocket 38 to receive a keeper rod 39, the end of which engages in the ears 35 before mentioned. The pad which has a length approximating that of the perforated supporting sheet or segment 28 is provided at its other end with a loop-like pocket 40 to receive a part 41 of a folding rule-like bar 42. The other part 43 of said bar is pivoted at one end to an end of the part 41 as indicated at 44 in Fig. 3.

45 45 indicates the stencil sheet which is provided at one end with openings 46 to engage the buttons 34 on the flange 33. This stencil sheet is somewhat longer than the ink pad so that its other end will extend beyond and over the groove 36 in the other end of the sheet or segment 28.

In applying a pad and a stencil to the supporting sheet or segment, this is preferably done while the segment is removed from the end heads of the cylinder, and in substantially a flat condition.

70 The pocket 38 of the pad is inserted into the groove 32 of the sheet or segment 28 and then a rod 39 is slipped through one ear 35, through said pocket 38 and into the other ear 35. The pad is then laid back upon the outside of the supporting sheet or segment to bring its other pocket into a position convenient with respect to

the groove 36 of said sheet or segment. The arm 41 of the folding rule-like device 42 is inserted into said pocket, with the other arm standing at an angle of about 90° thereto. The pocket with said arm 41 therein may now be placed in 5 said groove 36.

That end of the stencil sheet 45 having the openings 46 therein, is engaged with the flange 33 with the buttons 34 thereof extending through said openings. This anchors one end of the stencil to the segment and inking pad. The stencil sheet is then laid back upon the inking pad, substantially taut so that it is smooth and flat. With the stencil sheet thus arranged, its other end will project slightly beyond the groove 36. 10 The other arm 43 of the folding rule-like bar 42 is now swung down into the groove 36, depressing an end part of the stencil sheet therein as shown in Fig. 5, and at the same time, drawing said end taut. As the bar 42 is so formed in 20 thickness as to have a snug fit in the groove 36, this will secure the associated end of the stencil sheet to the supporting sheet or segment. It is apparent that the supporting sheet or segment, along with the pad and the stencil forms 25 a unit, ready for attachment to the end heads.

To apply this unit, the retainers 31 on the flanges 27 of the heads 26, are turned to extend in the direction of the length of the supporting sheet or segment which is now applied to the 30 flanges 27. The retainers 31 will now pass through the marginal openings 30 of the supporting sheet or segment after which said retainers are swung to extend crosswise of the openings. This locks the unit, comprising the segment, inking pad and 35 stencil, upon the end heads.

After the ink has been applied to the inside of the supporting sheet or segment, the machine may be operated in the conventional manner. Should it be desired to do multi-color work, the 40 unit with one ink thereon may be removed and another unit substituted in its stead.

The structures mentioned are simple and efficient for their intended purpose.

While in describing the invention, I have referred in detail to the form, arrangement and construction of the various parts thereof, the same is to be considered only in an illustrative sense so that I do not wish to be limited thereto except as may be specifically set forth in the 50 appended claims.

I claim as my invention—

1. A device of the class described including, in combination, a supporting frame, a printing cylinder, an impression roller, and a rectangular bearing block having lateral slots in the ends thereof adapted to slidably engage the sides of said supporting frame, said bearing having transverse extensions adapted to rotatably receive 55 said impression roller.

2. A device of the class described including, in combination, a supporting frame, a printing cylinder, an impression roller, a rectangular bearing block having lateral slots in the ends thereof 60 adapted to slidably engage the sides of said supporting frame, said bearing having transverse extensions adapted to rotatably receive said impression roller, and a substantially L shaped locking bar pivotally mounted on the lower face 70 of said bearing block adapted to releasably engage said supporting frame whereby to lock said impression roller in spaced relation with respect to said printing cylinder.
